Attorney

UNITED STATES PATENT OFFICE.

SORABJI DHUNJIBHOY, OF MARHA TAL, INDIA.

RAILWAY-TRAIN-STOPPING DEVICE.

Application filed August 20, 1924. Serial No. 733,228.

To all whom it may concern:

Be it known that SORABJI DHUNJIBHOY, a subject of the King of England, residing at Marha Tal in the Province of Jubbulpore, India, has invented certain new and useful Improvements in Railway-Train-Stopping Devices, of which the following is a specification.

This invention relates to a railway stopping train device and has for its principal object to produce a simply constructed and easily applied apparatus whereby in the event of the displacement of any portion of a bridge over which the railway train is adapted to pass, the brake on the approaching train will be actuated and the train stopped before the same has reached the point of danger.

Another important object of the invention is to provide a railway train stopping device of the above mentioned character, which is adapted for use upon railway bridges and is particularly constructed for the purpose of preventing the train from passing over the railway bridge if the same has become damaged or otherwise injured thereby preventing the passing of the train over the bridge due to the bridge being flooded or otherwise destracted.

A still further object of the invention is to provide a railway train stopping device in connection with the bridge or a tunnel whereby the positive actuation of the mechanism for cooperation with the air brake system on the train will assure the proper and immediate stopping of the train before the same has reached the point of danger.

Another important object of the invention is to provide a railway train stopping device which is simple in construction, inexpensive, strong, durable and further well adapted for the purposes for which it is designated.

A still further object of the invention is to provide a train stopping device of the above mentioned character, which is automatic in its operation and is furthermore provided with means for properly actuating the brake setting mechanism at all times.

Other objects and advantages of this invention will become apparent during the course of the following description.

In the accompanying drawings forming a part of this specification and in which

like numerals designate like parts throughout the same:—

Figure 1 is a side elevation of a section of a railway track together with a bridge over which the track passes and showing the manner in which the train stopping device is associated therewith.

Figure 2 is a top plan view of the device.

Figure 3 is a detail view of the trip mechanism and the support therefor.

Figure 4 is a fragmentary view of the bridge showing a modified form of trigger actuating means.

Figure 5 is a side elevation of the signal arm and supporting post.

Figure 6 is a detailed sectional view of a ring and showing a portion of the cable passing through the ring.

In the drawings wherein for the purpose of illustration is shown the preferred embodiment of my invention, the numeral 1 designates a fixed or stationary railway bridge having the usual pillars 2. The bridge 1 is furthermore provided with a longitudinally extending conduit 3 which is adjacent the railway tracks 4 which pass over the bridge and adapted to extend through the longitudinally extending conduit 3 is an operating cable 5.

Upon opposite sides of the bridge 1 and spaced at a suitable distance therefrom are the signal supporting posts 6 and 7. As both of these signal supporting posts are of the same construction it is deemed only necessary to describe one and the description of one will suffice for both. The signal supporting post 6 has at its upper end and pivotally mounted therein the usual signal arm 8. Normally the signal arm 8 extends in a downward position and lies flush against the supporting arm 6. The signal post 8 is furthermore kept in its inoperative position by means of the weighted arm 9 which is pivoted at 10 to the supporting post 6 and is connected to the signal arm 8 by means of a rod 11 whereby the weight 12 upon the arm 9 will cause the signal arm 8 to normally be disposed in a downwardly extending position. The signal arm 8 is furthermore adapted to carry the trip lever 13 and the purpose of this trip lever 13 will be hereinafter more fully described.

The free end of the arm 9 is connected to the operating cable 5 by means of any

suitable fastening member and the cable 5 is furthermore adapted to pass through auxiliary supporting members 14 which are supported in the ground and furthermore keep the cable 5 the ends of which are connected to the arm 9 on the signal supporting posts 6 and 7 respectively and the weight on the arms will normally keep the operating cable 5 in a taut position and at the same time support the signal arm 8 in an inoperative position.

Connected at its upper end to the operating cable 5 which extends longitudinally through the conduit 3 in the bridge 1 is a vertical cable 15. As there may be as many cables 15 as desired and associated with the pillars 2 of the bridge 1 it is only thought necessary to describe one in order to fully set forth the construction and operation of these members. The pillars 2 of the railway bridge 1 are furthermore provided with spaced guide rings 16 through which are adapted to pass a vertical cable 15 and the vertical cable 15 may be fastened or otherwise secured to the pillars 2 at a suitable point from the bridge 1 for the purpose of properly actuating the operating cable 5 hereinafter to be more fully described.

In operation should the bridge 1 in any way become destroyed, that is to say if any of the pillars 2 become broken the vertical cable 15 will be caused to be pulled downwardly and thereby draw downwardly on the operating cable 5. This action will cause the lever 9 to be raised to a horizontal position and thereby force the signal arm 8 upwardly and extend it into a horizontal position whereby the brake trip 13 is set in proper position and it is then in position to act upon an arm or lever 17 carried by the locomotive and which is connected with the air or power of brake mechanism in the manner such that when the same is operated by contact with the said brake trip it will automatically throw into operation said brake mechanism and effect an immediate stopping of the train before reaching the danger point. As these brake systems are so well known and as they form no part of the present invention it is not deemed necessary to further illustrate them only in the manner as above described.

In the modification as shown in Fig. 4 of the drawings, the bridge 1 has a pair of chains or other supporting members 18 depending therefrom and the opposite end of the supporting chains are adapted to support a plank 19. The plank 19 which is supported by the supporting chains 18 is arranged at a predetermined height with respect to the bridge and the purpose of this plank is to support a weight 20 which is connected to a transverse cable 21 similar to the transverse cable 15 and which is at its upper end connected to the longitudinal ex-

tending cable 5. Normally the weight 20 is supported upon the plank 19 and when in this position the transverse cable and the operating cable 5 are in an inoperative position. Should the rise of water over the water mark level which would be in the present instance at the height of the plank 19, cause a sudden rush of water to dislodge the plank 19 from under the weight 20, the weight 20 will immediately cause the transverse cable 21 to draw downwardly upon the operating cable 5 and in turn cause the setting of the brake trip 13 into an operative position in the manner similar to that above described.

In Fig. 7 a modification is shown wherein the setting of the signals is controlled from a distance by a manually operated means located in any convenient place, such as a station house or the like, illustrated at 25 in the drawings. Supported in this house is a pivoted lever 26, the latter having a pawl 27 carried thereby for engagement with a suitable toothed quadrant 28 whereby the lever may be held in the desired position. Connected to the lever 26 is the actuating cable 29, the latter extending through suitable guide means 30 positioned along the tracks 31.

This cable 29 is further adapted to extend around the guide roller 32 which is secured to the lower portion of the signal supporting member 33 and is secured to the outer end of the weighted arm 34 in the manner similar to that shown in Fig. 5 of the drawings and heretofore more fully described.

In Figs. 7 and 8 of the drawings the signal arm 35 is connected to the trip supporting arm 36 which carries the trip element 37 at one end thereof by means of the rod 38. The rod also is connected to the weighted arm 34 so as to cause all of the arms to operate simultaneously. The trip arm 36 is pivotally supported on the supporting member 33 directly below the signal arm, as shown at 39 in Fig. 8 of the drawings, and is supported so as to permit the lever carried by the locomotive to be actuated thereby, thus effecting the immediate stopping of the train should the same accidentally pass the signal when the same is set.

In Fig. 9 a still further modification is shown wherein the signal arm 35 extends on one side of the support 33 and the trip supporting arm 36 extends on the opposite side of the support. The pivotal ends of the signal arm and trip arm are connected by means of the rod 40, and the rod 38 is employed for causing the simultaneous operation of the signal arm and the trip arm with the weighted arm in the manner as above described. The operation is identical with the device shown in Figs. 7 and 8.

It will thus be seen from the foregoing

description that a train stopping device has been provided which is adapted for use upon railway bridges and may also be used in tunnels or in any other suitable place desired. With a device of this kind it will prevent accidental passing over the danger point due to the operator of the vehicle upon noticing the signal arm and will automatically set the air brake system in operation to cause the immediate stoppage of the train before the same has reached the danger point. A device of this character is very efficient and the simplicity of the same renders it very easily to be placed into use and does not require any attention other than setting the device into proper position.

From the foregoing description of the construction of my improved apparatus, it will be seen that I have provided a simple, inexpensive, and efficient means for carrying out the objects of the invention, and while I have particularly described the elements best adapted to perform the functions set forth, it is obvious that various changes in form, proportion and in the minor details of construction may be resorted to, without

departing from the spirit or sacrificing any of the principles of the invention.

What I claim as new and desire to secure by Letters Patent is:—

A train stopping device comprising in combination with a track and a post adjacent the track, a signal arm pivoted to the post and arranged to swing over the track, a trip member carried by said arm and located at a point between the pivot of the arm and that end edge thereof which may be disposed over the track, said trip member extending below the lower edge of the arm, a second arm pivoted to the post at a point below the first mentioned arm, a weight mounted upon one end portion of the second mentioned arm, a cable connected with the other end portion of the second mentioned arm and adapted to be extended along the track and a rod connecting the weighted end portion of the second mentioned arm with the first mentioned arm at a point between the pivot of the first mentioned arm and the trip.

In testimony whereof I affix my signature.
SORABJI DHUNJIBHOY
